UNITED STATES PATENT OFFICE.

THOMAS S. ALLEN, OF MILWAUKEE, WISCONSIN, ASSIGNOR, BY MESNE ASSIGNMENTS,
TO ALLIS-CHALMERS MANUFACTURING COMPANY, A CORPORATION OF DELA-
WARE.

BRUSH-HOLDER FOR DYNAMO-ELECTRIC MACHINES.

1,084,384.

Specification of Letters Patent.

Patented Jan. 13, 1914.

Application filed February 28, 1910. Serial No. 546,539.

To all whom it may concern:

Be it known that I, THOMAS S. ALLEN, a citizen of the United States, residing at Milwaukee, in the county of Milwaukee and State of Wisconsin, have invented certain new and useful Improvements in Brush-Holders for Dynamo-Electric Machines, of which the following is a full, clear, and exact specification.

10 This invention relates to brush holders for dynamo-electric machines, and particularly to brush holders adapted to be employed with commutators of high speed machines.

15 In high speed direct current machines, there is frequently considerable sparking and chattering of the brushes and the operation of the commutator and brushes is otherwise unsatisfactory particularly when brush holders having spring actuated pressure fingers or followers are employed. This

20 is due largely to slight irregularities of the rapidly revolving commutator surface and to the fact that the pressure fingers which have small inertia, are set in rapid vibration

25 by oscillation of the springs caused by sudden outward movements of the brushes.

The object of the present invention is to provide a brush holder which is especially adapted for use on high speed machines and has a construction such that the vibration of the brush and pressure finger, due to slight irregularities on the commutator surface, will be reduced, and the efficiency and operation of the commutator and brush will

35 be improved.

To reduce the vibration of the brush and pressure finger or follower I provide on the latter, preferably at the outer free end thereof, a weight which increases the inertia of the pressure finger and renders it less susceptible to vibration. Preferably the pressure finger does not bear directly on the brush, but a yieldable member such as a spring is arranged between the brush and the pressure finger, so that when the brush is moved outwardly by an irregularity on the commutator surface very little or no movement whatever will be transmitted to the pressure finger on account of its increased inertia provided by the weight and because the yieldable member between the brush and pressure finger will give or yield sufficiently to accommodate the movement of the brush.

My invention may be further briefly summarized as consisting in certain novel details of construction and combination and arrangements of parts which will be described in the specification and set forth in the appended claims.

Reference is had to the accompanying sheet of drawings, wherein—

Figure 1 is a side elevation of a brush holder constructed in accordance with the preferred form of my invention, the holder being provided with a brush which bears against the commutator, a portion of which is also shown; and Fig. 2 is a plan view of the same.

Referring now to the figures of the drawing, 10 represents a cast metal brush holder body which is provided at one end with a rectangularly-shaped brush guide or socket 11, which receives a brush 12, the inner end of which is adapted to bear on the commutator 13, the brush being connected to the brush holder body by the usual shunt conductor 12a. The brush holder body is provided also with an annular socket 14 adapted to receive a supporting stud to which the brush holder may be secured by means of a set screw 15, and extending outwardly from the rear portion of the holder is a pair of arms 16 to the free ends of which is pivotally secured by means of a pin 17 a forked pressure finger or follower 18, the free end of which preferably extends over and is substantially in line with the brush 12. The follower is pressed yielding toward the brush holder by means of a spring 19, one end 20 of which is connected to the brush holder body, and the opposite end 21 of which is connected to a member 22 adapted to engage in any one of a number of notches 23 generally provided in the brush holders of the type here shown.

In the usual brush holder constructions, the follower bears directly on the brush and inasmuch as it has very little inertia, any slight irregularity on the surface of a high speed commutator will throw the brush and follower outward, stretching the spring, and as the irregularity passes the brush and the latter again moves inward, the tension of the spring is decreased. As the movement of the brush and follower, particularly in a high speed machine, is very rapid, the spring tends to oscillate before it comes to

rest and tends to cause the pressure finger and brush to vibrate, producing more or less of a chattering noise and sparking at the commutator surface. To avoid this vibration in the brush and follower, I provide on the follower a weight 24 so as to increase its inertia, the weight being preferably cast integral with the follower and being located at its free end opposite the brush, 10 and I arrange between the follower and brush a yieldable member 25 which in this case is in the form of a leaf spring secured to the follower.

By providing on the pressure finger the 15 weight 24 and by arranging the yieldable member 25 between the pressure finger and the brush, the vibration of the brush and finger is greatly reduced for the reason that if there is an outward movement of the brush, due to a slight irregularity on the 20 commutator surface, the spring 25 will yield sufficiently to accommodate this movement without causing any material shifting of the pressure finger and a stretching 25 of the spring 19 chiefly because of the inertia of the pressure finger produced by the addition of the weight 24 at its outer free end. It is not essential that the weight be at the free outer end of the follower, but I 30 prefer that it be so located for the reason that when located as shown it is more effective than if it were distributed over the

pressure finger or were arranged nearer the pivotal support 17.

I do not desire to be confined to the exact details shown but aim in my claims to cover all modifications which do not involve a departure from the spirit and scope of my invention.

What I claim as new and desire to secure 40 by Letters Patent is:—

1. In a brush holder, a body portion having a brush guide or socket, and a spring actuated pressure finger pivotally mounted on the body portion, and provided at its free 45 end with an integrally formed weight to increase its inertia, and a spring connected to the pressure finger intermediate its ends and adapted to engage the brush.

2. In a brush holder, a body portion having a guide for a brush, a spring actuated follower having a weighted end portion and adapted to hold the brush against the collector surface, and a spring attached to said follower intermediate its pivotal point and 50 the weighted end portion and bearing on said brush.

Milwaukee, Wisconsin, February 9, 1910.

In testimony whereof I affix my signature, in the presence of two witnesses.

THOMAS S. ALLEN.
